CABLE SHEATH EXTRUSION PRESS

Conrad C. Jacobson, Glen Ridge, N. J., assignor
to John Robertson Co., Inc., Brooklyn, N. Y., a
corporation of New York

Application September 21, 1933, Serial No. 690,328

7 Claims. (Cl. 207—2)

My present invention relates to cable sheath extrusion apparatus and aims to provide certain improvements therein.

Among the objects of my invention are the following: (1) to provide an apparatus of the kind described, in the operation of which the quality of the cable sheath produced will not be dependent upon the human factor of the operator in charge of the apparatus; (2) to provide an apparatus wherein the inherent defects due to welds and oxide inclusions in cable sheath will be eliminated; and (3) to provide an apparatus wherein the flow lines in the cable sheath are reduced to a minimum. The invention also contemplates the provision of novel features in the construction and in the assembling of the various constituent parts of the apparatus whereby the assembly, disassembly, inspection and repair of any of the constituent parts is greatly facilitated, and wherein the product of said apparatus will be more uniform, homogeneous and superior to lead cable sheath heretofore produced.

With the foregoing and other objects in view, my invention may be said to constitute an improvement over earlier apparatus for the same purpose invented by me and for which patent applications are now pending.

My present invention will be better understood from the detailed description which follows, when considered in conjunction with the accompanying drawings, wherein:—

Figure 1 is a vertical section through the apparatus taken substantially along the plane of the line 1—1 of Fig. 2.

Fig. 2 is a top plan view of the apparatus.

Fig. 3 is a side elevation partly in section, as viewed from the left of Fig. 1.

Fig. 4 is an enlarged sectional view of a detail of the invention.

Referring to the drawings, let A indicate the furnace and its attendant parts in their entirety, B the extrusion press as a whole, and C the die-block, said parts being in the nature of separate and distinct units adapted for assembly into one constituent whole.

The furnace A, as shown, comprises an enclosing furnace shell *a* having three elements or pegs *2a* adapted to be supported upon a base or groundwork D and adjustable to hold the furnace in proper vertical position. The furnace is lined, as is customary, with fire brick *3a* and provided with a fire box *4a* and with a suitable vent opening *5a*. Extending inwardly from the shell *a* near its top is supporting flange *6a* upon which rests an outwardly-extending flange *e* at the top of

a melting kettle E which sets within the furnace housing above the fire box. Eccentrically disposed within the melting kettle and dependently supported by the top or cover thereof, is a melting chamber *2e*, the bottom of which is disposed in spaced relation to the bottom of the melting kettle and has openings *3e* therein, providing communication between the melting chamber and the melting kettle. Above the melting chamber is a charging hood *4e* and a roller table *10e* upon which the lead pigs are charged into the melting chamber. The cover of the melting kettle in spaced relation to the charging chamber extending therethrough is formed with a dome-shaped portion *6e* through the side of which extends a pipe *1e* (Fig. 2) leading from a source of non-oxidizing gas *8e* and provided with a valve *9e* controlling the admission of such gas to the interior of the kettle. Through the top of the dome-shaped portion *6e* extends a valve rod *f*, at the outer end of which is secured a hand wheel *2f*, and to the inner end of which is secured a plug valve *F*. The valve rod *f* is preferably in the form of a tubular member having a channel or bore *3f* extending longitudinally therethrough, which channel is continued through the valve plug *F*. Above the normal surface of the molten metal within the melting kettle the valve rod *f* is provided with lateral openings *4f* for establishing communication between the channel in the valve rod and the space above the surface of the metal in the kettle. The channel or bore in the valve rod from a point just below the lateral openings *4f* to the outer end of the rod is somewhat enlarged, and extending into said enlarged bore is a second rod or pin *G*, the inner end of which is formed to constitute a valve adapted to seat against the shoulder formed by the bores of different diameter in the valve rod *f*. The outer end of the rod *G* extends through the top of the rod *f* above the hand wheel *2f* and is provided with a hand wheel *g*. Through a suitable connection (not shown) between the rod *G* and the outer end of the valve rod *f* the inner end of the rod *G* is adapted to be brought into and out of engagement with the shoulder valve seat formed between the bores of different diameters within the valve rod *f* and thereby function to establish or cut off communication between the lower portion of the bores through the valve rod *f* and the space above the metal in the kettle. Suitable glands and packings are provided for the rods *f* and *G* to prevent the escape of gas therethrough or therearound.

Extending through the bottom of the kettle E

in axial alignment with the valve rod *f* is one end of a bent or angular draw-off tube *H* which extends into the kettle above the bottom thereof and at said end is provided with a valve seat for 5 the plug valve *F*. For moving of the plug valve onto and from its seat, a suitable connection (not shown) may be provided between the rod *f* and a bushing *10e* carried by the top of the dome member *6e*. The lower end of the draw-off tube 10 *H* extends through an opening *7a* in the furnace wall and may be suitably connected by welding or otherwise within an enlarged end in a passage *j* in the extrusion press cylinder *J*, said passage leading centrally into the bottom of a vertical 15 extrusion chamber *2j* in said cylinder. The draw-off tube *H* may be protected against excessive heat from the fire box by being enclosed in a suitable cast iron or refractory jacket *h* which may extend from a point just below the 20 melting kettle to a point in close proximity to the extrusion press cylinder. For draining out all of the molten metal from the melting kettle *E* should such become necessary or desirable, I have provided said melting kettle at its bottom 25 with a draw-off conduit *11e*, the outer end of which is formed with a valve seat upon which a valve *12e* carried by a rod *13e* is removably seated. The conduit *11e* is supported by a fitting *8a* extending through an opening *9a* in the furnace 30 wall, said fitting also providing a guide for the valve rod *13e* and having a discharge spout *10a*.

The extrusion press *B* is of the type having a vertically reciprocable ram *K* carried by a cross-head *L*, which, in turn, is rigidly connected to a 35 pressure cylinder *M* through four tension rods or columns *N*. Also carried by the cross-head *L* and depending therefrom is a pair of plungers *O* which are movable in backing cylinders *P* carried by the press frame.

40 The extrusion chamber *2j* at its bottom where it communicates with the passage *j* is formed with a tapered valve seat *3j* upon which is seatable a valve *R* carried by a valve rod *r* which extends axially through the ram *K*. The seating 45 surface of the valve *R* is correspondingly shaped to the valve seat *3j* and may be faced with a non-ferrous metal *2r* such as Monel metal, to prevent scoring of either the valve or the valve seat and thus insure against leakage when the valve is 50 closed. To further insure proper seating of the valve it is rockingly carried by the valve rod through the medium of a rounded bottom pocket *3r* formed in the top of the valve and into which 55 extends and seats an enlarged head *4r* at the lower end of the valve rod, which head preferably has a curved or rounded surface of greater curvature than the bottom of the socket, the valve and valve rod being connected together through the medium of a T-head key joint which is held 60 against unlocking by a pin *5r* extending through said parts. For guiding the ram in its movements within the cylinder *2j* and to keep it from contacting engagement with the wall of said cylinder, I cause said ram to pass through a gland 65 *4j* which is screw-threaded into the outer end of said cylinder.

To maintain the extrudable metal reaching the chamber *2j* in the molten state any suitable means may be employed. I prefer, however, to 70 heat the cylinder by circulating therein heating fluid, and to accomplish this I form the upper portion of the cylinder of two concentrically disposed engaging members *J'* and *J²*, the member *J'* having a reduced cylindrical outer surface provided with spaced annular grooves *5j* and the

member *J²* having an inner cylindrical surface provided with spaced annular grooves *6j*, the member *J²* being preferably shrunk upon the member *J'* so as to bring the annular grooves into complementary relation. The resulting annular 5 grooves are suitably formed for providing fluid communication therebetween and have connecting means for receiving and discharging the heating fluid. The cylinder *J* near its top is provided with a second group of communicating 10 annular ducts *7j* in which cooling fluid may circulate whereby to maintain the temperature around the gland *4j* substantially below the congealing point of the molten metal within the cylinder. For maintaining the metal in the passage 15 *j* and in the discharge passage *8j* leading from the cylinder, the lower portion of the cylinder is annularly grooved, as indicated at *9j*, for accommodating suitable heating means, preferably gas fired means.

20 The cylinder *M* is disposed below the floor or foundation upon which the press is supported and is movable downwardly with the ram *K* upon the admission into said cylinder of hydraulic fluid through a fixed piston *m* through a pipe *2m*. 25 Upward movement of the ram *K* is accomplished by opening the passage leading into the cylinder *M* to waste and admitting hydraulic pressure into the backing cylinders *P* through the pipes *p*.

The ram *K* is connected to the cross-head *L* in 30 a manner to permit the ready disassembly of said parts so as to facilitate the inspection and repair of the ram when necessary, by having said ram provided with an enlarged cylindrical portion *k* at its outer end whereat it extends through a 35 central opening *l* in the cross-head, and said enlarged portion *k* being formed with annular grooves *2k* spaced apart a distance corresponding to the thickness of the press head, and said ram being held in assembled relation in said 40 press head by split rings *3k* which engage in the grooves *2k* and are detachably held to the press head by bolts *4k*.

The valve rod *r* which extends through the ram *K* is mounted to have a close sliding fit 45 therein and adapted for limited relative movement with respect to said ram. To provide the close fit aforementioned and preclude scoring and consequent binding of the valve rod within the ram, the latter is provided with non-ferrous 50 bushings *5k* and *6k*, the latter being held within the ram by a sleeve *1k* held in position by a threaded gland *8k*.

For operating the lead valve *R* to cause and maintain the seating thereof upon the valve seat 55 *3j*, there is provided valve operating means consisting of a hydraulic cylinder *S* formed in a casting *T* rigidly supported by the element *J²* of the press cylinder *J* by rods *t* and within the cylinder *S* is movable a piston *s* having a piston rod 60 *2s*, which, at its outer end terminates in an enlarged head *3s* having a central cavity or socket into which the outer end of the valve rod *r* fits. The outer end of the cylinder *S* is closed by a head *4s* having a central opening *5s* therethrough, 65 within which is connected the end of a pipe *6s* for conducting hydraulic fluid to and from said cylinder. The hydraulic fluid is supplied to said cylinder *S* simultaneously with, and under the same pressure, as the hydraulic fluid supplied to 70 the pressure cylinder *M*. The direction of flow of said hydraulic pressure to the cylinders *M* and *S* is controlled by the handle *2t* on the reversing valve *T*. To prevent injuring the apparatus should the operator fail to reverse the flow of 75

hydraulic fluid at the end of the downward extrusion stroke, there is provided a safety device U (Fig. 3) which comprises a valve *u* having a valve pin *2u* normally held seated by the fluid pressure acting upon the piston in the cylinder S, said valve *u* being adapted to be unseated to bypass the fluid from said cylinder through the medium of the pivoted lever *3u* and rod *4u* which is guided through the press head L and which rod at its lower end is provided with an enlargement *5u* which is adapted to be engaged by said press head L upon reaching its lowermost position and thereupon act through the rod *4u* and lever *3u* to raise the valve U off its seat.

15 The discharge passage *8j* leading from the extrusion chamber of the press has connected thereto one end of a connecting pipe V, the opposite end of which is connected to a receiving passage *c* in the die-block C. Within the pipe V 20 is slidably fitted a tube *2v* of somewhat greater length than the pipe V, the ends of said tube being formed to seat against shoulders in the pipe connecting ends of the passages *8j* and *c* and make leak-tight joints therewith. To facilitate 25 the connection between said parts to insure efficient leak-tight joints at the ends of the tube *2v*, the connecting pipe V is provided at its opposite ends with a right hand and a left hand thread for connection with correspondingly threaded openings in said respective parts. To facilitate tightening said connecting pipe it may be formed intermediate its ends with a wrench-engaging portion *v*.

30 The die-block C which is designed to receive 35 the extruding metal in the molten state and extrude it in the congealed state, consists of a suitable member *2c* having an extrusion chamber *3c* extending axially therethrough and within which is axially positioned a core W. The 40 extrusion chamber *3c* is somewhat enlarged at the region of the receiving passage *c* leading thereto, and within said enlarged portion of the chamber is an equalizer ring X. The enlarged portion of the extrusion chamber within which 45 the equalizer ring is located, is of such form that the equalizer ring provides an annular conduit *4c* surrounding the ring and communicating with the receiving passage *c*, and said ring has a plurality of circumferentially spaced radial openings *x* therein connecting the annular conduit with the chamber proper around the core. For 50 draining the molten lead from the die-block it may be provided with a conduit *9c* leading from the bottom of the annular chamber *4c*, and said conduit might have interposed therein a valve *10c* which is operable from the exterior of the die-block. The valve, when opened, will permit the liquid lead to pass from the conduit *9c* down and out through the drain pipe *11c*.

55 In the operation of the apparatus hereinbefore described, let it be assumed that during the heating of the lead kettle E the lead is melted therein in an atmosphere of an inert gas. Before starting the extrusion operation the valve F will be closed, the valve R will be open and the ram will be in its uppermost position preparatory to commencing the extrusion stroke. By opening the valve *9e*, gas from the tank *8e* will flow into the top of the kettle above the molten lead therein. The valve G is thereupon opened, whereupon the gas from the kettle will flow through the valve stem *f*, draw-off tube H into the cylinder *2j*, through the connection pipe V and through the die-block extrusion chamber *3c*. Enough gas is

permitted to flow through the apparatus to thoroughly evacuate the atmospheric oxygen therefrom. The valve G is then closed and the valve F opened, thus allowing the molten lead to flow into the extrusion cylinder and die-block, 5 entirely filling the extrusion cylinder, the connecting conduit between the cylinder and the die-block, and as much of the die-block as possible before said metal congeals near the delivery end or die therein. The valve F will remain 10 open during the entire operation of the press.

To start the extrusion operation, the reversing valve handle *2t* is placed in position to supply hydraulic pressure to the extrusion cylinder M and valve operating cylinder S. This pressure 15 will cause the cylinder M to move downwardly and carry with it the ram K, and also cause the piston *s* to move the valve rod *r* downwardly.

After about one inch travel of the ram, the 20 valve R will seat if the hydraulic pressure on the valve control piston *s* had not already seated the valve, thus closing the passage to the melting kettle. The molten lead in the extrusion cylinder *2j* will then be forced through the discharge passage *8j* and through the connecting conduit 25 V to the die chamber conduit surrounding the equalizing ring and through the radial openings therein to the extrusion chamber proper of the die-block. As the molten lead is moved towards the die it is gradually being congealed and cooled 30 to a temperature of approximately 350° F., and leaving the die at an extrusion speed which is controlled by the rate of hydraulic water supplied to the hydraulic cylinder M. At the end of the extrusion stroke the reversing valve handle 35 is moved to a position whereat the valve will function to permit the water from the cylinders M and S to go to waste and to simultaneously supply hydraulic fluid under pressure to the backing cylinders P to force the cross-head L 40 upwardly and move the extrusion ram upwardly in its cylinder. After the valve rod *r*, which will move upwardly with the ram K due to the frictional engagement therebetween, has traveled a distance of about one inch, its further movement 45 will be arrested by the top of the rod *r* abutting the head *3s* of the piston rod *2s*, which by this time has been moved into abutting engagement with the under side of the fixed cylinder S. The ram K, it will be noted, does not come into contact with the wall of the extrusion cylinder *2j*, thereby eliminating the possibility of scoring or cutting of the extrusion cylinder and the contaminating of the extrudable metal with steel chips.

55 The heating and cooling of the extrusion press and die-block may be automatically controlled by the circulation of suitable liquids through the annular openings in the extrusion cylinder and in the die-block and maintained by suitable stand- 60 ard temperature control equipment.

The heating and cooling fluids employed may be superheated steam, mercury, a mixture of diphenyl oxide and diphenyl or other suitable liquids, and of course, pumping devices suitable 65 for operation with the chosen heating substance will be employed.

From the foregoing detailed description of the apparatus and the manner of its operation, it will be appreciated that I have provided a cable 70 sheath extrusion device which is relatively simple in construction, efficient and foolproof in its operation, and wherein the inherent defects in cable sheathing such as welds and oxide inclusions will be completely eliminated, and wherein 75

the presence of flow lines will be reduced to a minimum. It will also be appreciated that although the present disclosure contains a preferred embodiment of my invention, I do not wish 5 to have the same construed as defining the limitations thereof, since it will be apparent that changes in construction may be resorted to within the range of engineering skill without departing from the spirit of the invention.

10. What I claim is:

1. A cable sheath extrusion apparatus comprising an extrusion cylinder, a ram reciprocable in said cylinder, and a valve in one end of the cylinder controlling the admission of molten metal thereinto, cooperating means on the valve and the ram whereby said valve is adapted for limited movement with the ram.
2. A cable sheath extrusion apparatus comprising an extrusion cylinder, a ram reciprocable in said cylinder, and a valve in one end of the cylinder controlling the admission of molten metal thereinto, cooperating means on the valve and the ram whereby said valve is adapted for limited movement with the ram and means for 15 moving the valve independently of the ram.
3. A cable sheath extrusion apparatus comprising a cylinder, a ram reciprocable in said cylinder, and a valve in one end of the cylinder controlling the admission of molten metal thereinto, and a valve rod extending axially through the ram.
4. A cable sheath extrusion apparatus comprising a cylinder, a ram reciprocable in said

cylinder, and a valve in one end of the cylinder controlling the admission of molten metal thereinto, and a valve rod extending axially through the ram, the valve being rockingly carried by the valve rod.

5

5. A cable sheath extrusion apparatus comprising a cylinder, a ram reciprocable in said cylinder, a valve in one end of the cylinder controlling the admission of molten metal thereinto, a valve rod extending axially through the ram, 10 and fluid pressure operable means for controlling the movements of the ram and the valve.

6. A cable sheath extrusion apparatus comprising a cylinder, a ram reciprocable in said cylinder, a valve in one end of the cylinder controlling the admission of molten metal thereinto, a valve rod extending axially through the ram, 15 and fluid pressure operable means for seating the valve, said means being rigidly supported by the cylinder in spaced relation thereto.

20

7. A cable sheath extrusion apparatus comprising a cylinder, a ram reciprocable in said cylinder, a valve in one end of the cylinder controlling the admission of molten metal thereinto, a valve rod extending axially through the ram, 25 fluid pressure operable means for controlling the movements of the ram and the valve, and a safety device comprising a second valve and means for opening said second valve at the end of the extrusion stroke for by-passing the fluid 30 from the fluid pressure operable means.

CONRAD C. JACOBSON.
